3 Claims. (Cl. 219—4)

This invention relates to improvements in the joining of wires and is a division of my prior U. S. application, Serial No. 481,068, filed under date of March 30, 1943, now Patent No. 2,371,438, dated March 13, 1945. In that specification there was described and claimed the process of joining wires by electric fuse welding and an apparatus for carrying out the process comprising a pair of spaced electrodes, for example of carbon, across which the wires to be joined are bridged, means for clamping the wires against at least one of the electrodes and a circuit including an impedance for passing current through the wires. The present invention comprises an improved form of apparatus for carrying out such process.

According to one feature of the invention we provide an apparatus for joining wires by electric fuse welding comprising an electrode against which wires to be welded are adapted to abut, said electrode being mounted to be movable in the direction of length of said wires, means for holding said wires against said electrode and means for connecting one side of an electric supply to said electrode and another side of the supply to said wires at a point away from said electrode and means restricting the movement of said electrodes.

The invention will be better understood from the following description taken in conjunction with the accompanying drawing in which;

Fig. 1 is a perspective view with parts of the casing broken away showing a hand tool for joining wires according to this invention and Fig. 2 is an enlarged detail view of the wire gripping mechanism incorporated in the tool.

The handle 1 carries two contact blocks 2 connected to a suitable electric supply. One of these blocks carries a metal blade 3 extending towards the front of the tool and carrying a button 4 extending outside the handle and a contact 5. Under the contact 5 is mounted an insulating block 6 to which is fixed a metal member 7 carrying a spring blade 8. The member 7 carries a contact 9 immediately below but not normally touching contact 5. The block 6 also carries a wire clamp shown on an enlarged scale in Fig. 2. This wire clamp consists of two fixed members 10 and 11 and a member 12 sliding between them. Coinciding apertures 13 are formed in the members 10 and 11 and an aperture 14, normally out of alignment with aperture 13, in member 12. A trigger 15 pivotally supported in the handle 1 on shaft 16 has a projection 17 extending through slots 18 in the fixed members 10

and 11 and engaging the slidable member 12, the arrangement being such that when the trigger is actuated it moves member 12 against a spring 19 to bring apertures 13 and 14 into alignment.

The spring blade 8 carries a carbon electrode 20 opposite the apertures 13. The blade 8 tends to move away from member 7 but its movement in this direction is restrained by the head of a screw 21 which is screwed into member 7 and locked by a nut 22, the screw passing freely through an aperture in blade 8. The movement of blade 8 towards member 7 is restricted by a screw stop 23 screwing into member 7 and held by a nut 24.

The members 10 and 11 are connected within the handle to the lower contact block 2. A shroud 25 carried by the handle 1 surrounds members 7, 8, 10, 11 and 12 as shown. The handle 1 is made in two halves secured together by screws and nuts 26 fitting into recesses in one half.

In operation the wires to be joined indicated at 27 are preferably twisted together and cut off level. It is, however, not essential to twist the two wires together; they may be placed parallel and close together. The trigger 15 is then operated to bring aperture 14 in member 12 into alignment with apertures 13 and the wires 27 to be joined are inserted through the aligned apertures until they abut against electrode 20 and push it back as far as it will go as determined by the adjustable screw stop 23. The trigger is then released and member 12 grips the wires against members 10 and 11. Button 4 is then depressed and connects the electric supply through carbon electrode 20, the pair of wires 27 and members 10, 11, 12. The weld is made, the ends of the wires against carbon electrode 20 fusing together and melting allowing the electrode 20 to move away from member 7 until stopped by screw 21, whereupon the circuit is broken by the wires being out of contact with electrode 20. Trigger 15 is actuated and the wires withdrawn.

The device shown is suitable for the fluxless welding of conductors in electric communication cables, and the like.

It is to be noted that the term wire is not restricted to circular wire, and may also include a flat thin strip of metal. Thus by the use of the apparatus described the wire of a coil winding may be welded to a strip of metal struck up from a terminal of the coil. Also another strip struck up from the same terminal may be weld-

ed to an external connecting wire. It is thus possible to produce an electrical equipment without any soldered joints, all joints being made by electrical fuse welding.

It is clear that the apparatus described could be modified to form a bench fitting.

The apparatus described is suitable for welding copper wires or resistance wires or copper wire to resistance wire, but brass, iron or aluminum wires require special treatment.

Joints produced by electric fuse welding have been found to possess a fine dendritic structure of the metal throughout the mass into which the two wires are fused and this mass is free from voids, whereas in gas welding the fused mass shows a coarse crystalline structure and includes many voids or gas pockets.

What is claimed is:

1. A device for joining wires by electric fuse welding including an electrode against which said wires to be welded are positioned to abut, means for supporting said electrode provided with a resilient mounting for the electrode thereon to be movable in the direction of the length of said wires, means for holding said wires against the pressure of said electrode, said holding means being positioned in constantly spaced relation to

the movable electrode, means for connecting one side of an electric power supply to the electrode and means for connecting the other side of said power supply to said holding means.

5. 2. A device for joining wires by electric fuse welding including an electrode against which said wires to be welded are positioned to abut, terminal means for supporting said electrode to be movable in the direction of the length of said wires, having a resilient mounting for the electrode thereon, means for holding said wires against the pressure of said electrode, means for connecting one side of an electric power supply to the electrode, means for connecting the other side of said power supply to said wires, means restricting the resilient movement of said electrode whereby current passes from said electrode to the ends of said wires to effect fuse welding thereof and the restricted movement of the electrode automatically breaks the fuse welding circuit.

10 15 20 25 3. A device as claimed in claim 2 wherein the resilient mounting for the electrode consists of a spring blade secured to a terminal bar and wherein stop means are provided to limit the relative movement of the spring blade relative to the terminal bar.

GILBERT GILLIVER.
